UNITED STATES PATENT OFFICE.

PHILIP H. THOMPSON, OF WALDRON, ARKANSAS.

DEVICE FOR PROTECTING SAFES AND VAULTS.

No. 846,523.

Specification of Letters Patent.

Patented March 12, 1907.

Application filed April 28, 1906. Serial No. 314,298.

To all whom it may concern:

Be it known that I, PHILIP H. THOMPSON, a citizen of the United States, residing at Waldron, in the county of Scott and State of Arkansas, have invented a new and useful Device for Protecting Safes and Vaults from Burglars, of which the following is a full, clear, and exact description, reference being had to the accompanying drawings, forming 10 a part of this specification.

The object of my invention is to secure more perfect protection of bank safes and vaults against burglars, and consists of a vessel, of glass or other fragile substance, containing a poisonous gas, liquefied or not, applied and fitted to the door of the safe or vault and so held in position by a locking device that should any one attempt to open the door by violence the vessel will be broken, allowing 15 the gas to escape and compelling the operator to desist from his work and leave the room.

Figure 1 of the accompanying drawings is a front elevational view of my device with part of the vessel broken away to show the 20 interior. Fig. 2 is a horizontal cross-sectional view.

My invention consists of only three parts — viz., a sealed gas-bearing vessel having one or more recesses let into it from the back side 25 for the purpose of allowing the handles, locking device, hinges, &c., to enter, so that the vessel can be fitted close to the door, a lock, and an elongated shackle to the lock.

A indicates the door of the safe or vault. 30 B is the handle. C is the combination-knob. D is the shackle of the lock. E is the head of the shackle, enlarged so as to hold it in position. F is the lock. G is the key to the lock.

D is the shackle of the lock.

E is the head of the shackle, enlarged so as to hold it in position.

F is the lock.

G is the key to the lock.

To apply my invention, after the door of the safe or vault is closed the vessel is fitted against the door. The shackle of the lock is passed through an opening or canal that is made in the vessel. As the shackle passes through, it fits around the neck of the handle or combination-knob, thus holding the vessel in position against the door. The lock is then fitted to the ends of the shackle and fastened. The lock is let into the vessel to protect it from violence.

I am aware that prior to my invention gas-bearing vessels have been made into safes and vaults. I therefore do not claim such a combination broadly; but

I do claim —

1. In combination with a safe or vault door of a vessel containing a gas or gas-producing liquid, said vessel constructed to be applied and removably secured after the door is locked, fitting over the handles and locking device of the door, substantially as described.

2. In combination with a safe or vault door of a vessel containing a gas or gas-producing liquid, said vessel covering the whole or a part of the front of the safe or vault, and a locking device for removably securing said vessel to the safe or vault, substantially as described.

PHILIP H. THOMPSON.
